COMMUTATOR DRESSER

Gustav Schoenfeld, Great Falls, Mont.

Application February 2, 1937, Serial No. 123,703

6 Claims. (Cl. 82—4)

This invention relates to a device for dressing the commutator of an electric motor, and one object of the invention is to provide a device of this character of such size and construction that it may be easily carried from one place to another by a workman and thus permit the workman to redress a commutator without taking the commutator to a shop.

Another object of the invention is to so construct the device that, when using it to dress a commutator, it may be applied to the shaft carrying the commutator and turned about the shaft which will be held stationary in a vise. It will thus be seen that use of a lathe is entirely eliminated.

Another object of the invention is to provide improved means for adjustably mounting the blade of the dresser and also to provide improved means for shifting the blade longitudinally of the commutator during a dressing operation and thus cause the commutator to be properly trimmed.

Another object of the invention is to provide improved means for mounting the device upon the shaft of the commutator.

The invention is illustrated in the accompanying drawings, wherein

Figure 1 is a view partially in section and partially in side elevation and showing the improved commutator dresser applied to the shaft of a motor in position to dress the commutator,

Figure 2 is a plan view looking down upon Figure 1,

Figure 3 is a view in end elevation looking from the left in Figure 1,

Figure 4 is a sectional view taken vertically through the device on the line 4—4 of Figure 1, and

Figure 5 is a sectional view taken on the line 40 5—5 of Figure 1.

The body of this commutator dresser is formed from a block of fiber or other material which will be strong and yet of light weight. A shoulder 2 projects from one side of the body and through this shoulder extends a shaft 3 formed with a circumferentially extending groove 4 so that a pin 5 which is driven into a socket 6 bored through the shoulder transversely thereof may engage in the groove and prevent longitudinal shifting of the shaft 3 while permitting free rotary movement of this shaft. The shaft 3, which may be referred to as an operating shaft or drive shaft, carries a small gear or pinion 7, and upon referring to Figures 1 and 2 it will be seen that the shaft 3 projects from the forward

end of the block and in spaced relation to the pinion 7 carries a pin 8 having its ends projecting from opposite sides of the shaft so that the extended ends of the pin may engage in notches or seats 9 formed in the shank 10 of 5 a crank 11. Therefore, the crank may be detachably applied to the shaft and the shaft rotated. The pinion 7 meshes with a large gear or pinion 12 secured by a set screw 13 upon a shaft 14 which is of greater length than the shaft 3 10 and extends through the body 1 adjacent the opposite side of the body from the shaft 3, as shown in Figure 4. This shaft is also formed with a circumferentially extending groove 15 to receive a pin 16 driven into a socket 17 formed 15 in the body and, therefore, this shaft will also be held against longitudinal movement while permitted to rotate freely. The forward end portion of the shaft 14 projects from the hub of the gear or pinion 12 and carries a pin 18 20 which extends transversely through the shaft with its end portions projecting from opposite sides thereof so that when it is desired to directly rotate the shaft 14 instead of transmitting rotary motion to it from the shaft 3 the crank 25 may be detached from the shaft 3 and applied to the forwardly projecting end portion of the shaft 14 with ends of the pin 18 engaged in the notches or seats 9. When the crank handle is applied to the shaft 3, rotary motion will be 30 transmitted from the small gear or pinion 7 to the large gear or pinion 12 and the shaft 14 will be slowly turned, whereas, when the crank is applied to the shaft 14, a more rapid rotation of the shaft 14 will be obtained.

The cutter 19 is formed of tool steel and is mounted in a passage or socket 20 formed vertically through a block 20' of fiber or other suitable material which is of light weight but strong. The upper portion of the bore or socket 20 is 40 enlarged to form a circular pocket 21 in which an internally threaded adjusting sleeve or nut 22 is seated and held against longitudinal movement by a pin 23 which is driven through the block from one end thereof and engages in a circumferentially extending groove 24 formed intermediate the length of the nut or sleeve 22. The portion of the socket 20 below the pocket 21 is rectangular in cross section and since the cutter 19 is of similar shape in cross section the cutter 50 will be prevented from turning in the socket. The upper end portion of the cutter is formed with a reduced stem 25 which extends upwardly into the pocket 21 and terminates in a threaded head 26 engaged in the threaded bore of the sleeve or 55

nut. Therefore, when the nut is turned, the cutter will be shifted longitudinally either upwardly or downwardly according to the direction in which the nut is turned and the sharpened lower end of the cutter disposed in proper relation to the commutator to be dressed. Alined openings 27 are formed through the portion of the sleeve or nut which projects upwardly above the block 20' in order that a nail or the like may be passed through these openings and thus permit the nut to be easily turned when the cutter is to be vertically adjusted. A set screw 28 which is received in a threaded opening 29 formed transversely of the block from one side thereof to the bore or socket 20 is provided in order that after the cutter has been vertically adjusted the set screw may be tightened and the cutter firmly secured in the adjusted position. It will thus be seen that the cutter cannot accidentally slip out of a set position and cause the commutator to be incorrectly cut during a trimming operation.

The block and the cutter carried thereby must be shifted longitudinally of the commutator during a dressing operation and in order to slidably mount the block there has been provided a U-shaped yoke 30 formed of steel or other strong metal. This yoke is disposed horizontally and its arms 31 extend through openings 32 drilled through the upper portion of the body 1 above the shafts 3 and 14. Set screws 33 are threaded through openings 34 leading from the upper end of the body 1 and when tightened firmly grip the arms 31 so that the yoke will be firmly held in place and prevented from shifting longitudinally. Openings 35 which are formed through the block 20' at opposite sides of the pocket 21 near the upper end of the block slidably receive the arm 31 and a threaded opening 36 is formed through the block above the opening 29 to receive the threaded shaft 14. From an inspection of Figure 1, it will be readily understood that when the shaft 14 is rotated its threaded engagement with the block 20' will cause the block to be shifted longitudinally upon the arm 31 of the yoke 30 and the cutter will be shifted along the commutator 37 from the rear end thereof towards the forward end of the commutator. The shaft 38 of the armature projects from the forward end of the commutator and during the dressing operation is engaged in a socket 39 formed in the lower portion of the body 1 midway the width thereof. The socket 39 tapers upwardly, as shown in Figure 3, to a narrow recess 40 and is lined by a sheet metal liner 41 which is placed there to receive a shaft of smaller diameter and can be easily withdrawn when a shaft of larger diameter requires it. A thrust bar 42 which is slidably mounted in a throat or seat 43 leading downwardly from the socket 39 is intended to engage under the shaft 38 and in order to vertically adjust the thrust bar there has been provided an adjusting screw 44 carried by a cam 45. This cap 45 is formed from the same kind of material as the body 1 and is secured thereto by screws 46 which pass through corner portions of the cap and into the lower portion of the body. A collar 47 which is of greater diameter than the width of the throat 43 is formed integral with or fixed to the screw 44 and this collar is seated in a socket 48 formed in the inner face of the cap about the opening 49 in which the screw loosely fits. By this arrangement the screw will be held against longitudinal shifting when the cap is secured to the body and since the inner end portion of the screw

is threaded into the threaded opening 50 formed in the bar 42 rotary motion of the screw will cause the bar to be shifted vertically. Therefore, the bar may be moved into engagement with the shaft 38 and sufficient binding action applied to the shaft to prevent the shaft from slipping out of the socket 39 while at the same time permitting the body to be turned about the same and the armature should be held stationary by a vise 51. Other set screws 52 are threaded through the cap to engage the bar 42 near opposite ends thereof and cause the bar to be firmly held in place with its upper face bearing against the shaft 38 for the full length of the shaft.

When this device is in use, the armature must be removed from the motor and secured in a vise. The portion of the motor shaft which projects from the forward end of the commutator 37 is engaged in the socket 39 and the adjusting screws then turned to shift the pressure bar 42 upwardly into engagement with the shaft. In view of the shape of the socket and the liner 41, shafts of different diameters may be received in the socket 39 and when the bar 42 is shifted upwardly the shaft will have a two point contact with the liner or opposite sides of the extension 40 and the bar will engage the shaft at a third point. The shaft will thus be firmly gripped and when the screws 53 are adjusted inwardly to move their inner ends into engagement with the pressure bar the body 1 will be held in engagement with the motor shaft but permitted to turn about the same. The cutter 19 will be out of contact with the commutator 37 during this operation. As soon as the body has been applied to the motor shaft, the cutter will be shifted towards the commutator by rotating the sleeve or nut 22 until it is very close to the commutator and the crank 11 will then be applied to the forwardly projecting end of the shaft 14 and turned by a hand grasping the crank handle so that the shaft will be turned to adjust the block 20' along the yoke until the cutter is at the rear end of the commutator. The body 1 is held stationary upon the shaft 38 with the other hand during turning of the shaft 14 by the crank. A final adjustment will then be imparted to the cutter to move its sharpened end into position to contact with the commutator and the set screw 28 tightened to secure the cutter against accidental displacement. The crank is then removed from the shaft 14 and applied to the shaft 3 and grasped so that when the body is released the crank may be used as a handle to turn the entire body about the shaft 38, as indicated by the dotted lines in Figure 3. During swinging movement of the body about the shaft 38, the shaft 3 will be turned in the extension 2 of the body and rotary motion transmitted by the gear or pinion 7 to the gear 12 which is fixed upon the shaft 14 and the shaft 14 will be slowly turned. It will thus be seen that as the body is swung about the motor shaft the cutter will trim the commutator and turning of the shaft 14 will cause the cutter to be fed longitudinally of the commutator toward the forward end thereof. In view of the ratio between the small gear or pinion 7 and the large gear 12, the shaft 14 will be turned very slowly and in the present instance the shaft 3 must be turned between ninety-seven and one hundred times in order to shift the cutter one inch along the commutator. The commutator will, therefore, be evenly and smoothly cut by the sharp edge of the cutter. If it is necessary to cut the commutator more than once in order to properly

trim it, the cutter will be disposed between two copper bars of the commutator and the crank handle transferred to the shaft 14 so that this shaft may be directly turned and the cutter 5 quickly shifted toward the rear end of the commutator. The cutter will then be longitudinally adjusted toward the commutator so that it will 10 cut the commutator as the device is again swung about the motor shaft and swinging movement imparted to the body about the motor shaft until the entire surface of the commutator has 15 been again trimmed. The device can then be removed from the motor shaft and put away until again needed. It will thus be seen that commutators of motors used for electric fans and the like can be very easily and quickly dressed and this accomplished without taking the armature to a shop to have the commutator dressed and the expense of this saved. It can, therefore, 20 be seen that by use of this device a great saving in both time and money will be realized.

Having thus described the invention, what is claimed as new is:

1. A device of the character described comprising a body adapted to be mounted upon a motor shaft for turning movement about the shaft, a track detachably carried by the body and extending laterally from said body in position to be disposed in spaced parallel relation to 25 the motor shaft and an armature carried thereby, a mounting shiftable along said track parallel to the shaft, a cutter carried by said mounting and adjustable radially of the armature whereby its cutting edge may be disposed in position to 30 trim the armature as the body is swung about the motor shaft, and means journaled in said body for swinging the body about the shaft and shifting said mounting along said track to move the cutter along the armature during movement 35 of the body and cutter about the shaft and armature.

2. A device of the character described comprising a body adapted to be mounted upon a motor shaft for turning about the shaft, a yoke 40 extending laterally from said body in position to dispose the yoke in spaced parallel relation to the motor shaft and armature carried thereby, a block slidably carried by said yoke and shiftable longitudinally thereon, a cutter carried by 45 said block and extending therefrom radially of the armature, means for adjusting the cutter toward and away from the armature to dispose its cutting edge in position to trim the armature as the body is swung about the motor shaft, and 50 means journaled through said body and rotatably supported thereby for swinging the body about the shaft and progressively shifting the block along said yoke and moving the cutter along the armature as the body is swung about the motor shaft.

3. A device of the character described comprising a body adapted to be mounted upon a motor shaft for turning movement about the shaft, a U-shaped yoke carried by said body in position 55 to extend rearwardly therefrom in spaced parallel relation to a motor shaft and an armature carried thereby, said yoke having its arms fitted into sockets formed in the body, a block slidable along the yoke and having passages through 60 which arms of the yoke extend, a cutter extending

through said block and projecting therefrom transversely of the yoke and radially of the armature, means carried by said block for adjusting the cutter longitudinally and shifting its cutting edge towards and away from the armature, and means for shifting said block along 5 said yoke and moving the cutter along the armature as the body is swung about the motor shaft.

4. A device of the character described comprising a body adapted to be mounted upon a motor shaft and swung about the motor shaft, a support carried by said body and extending rearwardly therefrom in position to dispose the support in spaced parallel relation to a motor shaft and an armature carried thereby, a block 15 slidable along said support, a cutter extending through a passage formed in said block laterally of the armature and having a threaded inner end portion, an adjusting sleeve rotatably mounted in said block and having threaded engagement 20 with the inner end portion of said cutter for adjusting the cutter longitudinally towards and away from the armature when the sleeve is turned, and means for shifting the block along 25 said support and gradually shifting the cutter along an armature as the body is swung about the motor shaft.

5. A device of the character described comprising a body adapted to be mounted upon a motor shaft and turn about the shaft, a lateral support 30 extending rearwardly from said body in spaced parallel relation to a motor shaft and an armature carried thereby, a block slidable along said support, a cutter carried by said block and extending therefrom towards the armature, means 35 for adjusting said cutter radially of the armature, a shaft rotatably carried by said body in spaced parallel relation to the motor shaft and having a threaded portion extending rearwardly 40 from the body and engaged through a threaded opening of said block, and means carried by the body for swinging the body about the motor shaft and transmitting rotary motion to the threaded shaft to adjust the block along said support and move the cutter longitudinally of 45 the armature as the body is swung about the motor shaft.

6. A device of the character described comprising a body adapted to be mounted upon a motor shaft and turn about the shaft, a support extending rearwardly from said body in spaced parallel relation to a motor shaft and an armature carried thereby, a block slidable along said support, a cutter carried by said block and extending therefrom towards the armature, means 50 for adjusting said cutter radially of the armature, a shaft rotatably carried by said body and having a threaded portion engaged through a threaded opening of said block, a large gear carried by said threaded shaft, a second shaft rotatable 55 carried by said body, a small gear carried by the second shaft and meshing with the gear of the threaded shaft, and a handle detachably engageable with the second shaft whereby the body may be swung about the motor shaft and 60 rotary motion slowly imparted to the threaded shaft to shift the block along said support and move the cutter along the armature as the body is swung about the motor shaft.
